UNITED STATES PATENT OFFICE.

E. T. DUKE, OF PLATTSMOUTH, NEBRASKA.

STOVE-DAMPERS.

Specification forming part of Letters Patent No. **71,368**, dated November 26, 1867.

To all whom it may concern:

Be it known that I, E. T. DUKE, of Platts-
mouth, Cass county, Nebraska, have invented
a new and useful Improvement in Stove-Damp-
pers; and I do hereby declare that the following
is a full, clear, and exact description thereof,
which will enable others skilled in the art to
make and use the same, reference being had to
the accompanying drawings, forming part of
this specification.

This invention relates to an improvement in
stove-dampers; and consists of two flat rings
hung by means of loops at the extremities of
the conjugate axis of an elliptical center-plate,
through the transverse axis whereof passes a
square key or shaft. A triangular guard,
slightly curved in the direction of its length,
is attached to each ring at places correspond-
ing with the extremities of the transverse axis
of the elliptical plate in such manner that the
straight line joining the central points of the
attachment of the guards to the rings at one
end passes through the extremity of the trans-
verse axis. The whole is to be made of any
suitable metal, sheet or cast iron preferred.

In the accompanying drawings, Figure 1 is
a vertical section of stove-pipe and damper,
showing same open. Fig. 2 is the like section,
showing the damper closed; and Fig. 3 is a
horizontal section thereof at line *x x*.

Similar letters of reference indicate corre-
sponding parts.

The position of pipe and damper might, how-
ever, be changed to horizontal, or inclined at
any angle.

A A is the stove-pipe; B B, two flat rings
hung by the loops *b b* at the extremities of the
conjugate axis of the elliptical plate C. D is
an angular shaft or key (diamond shape pre-
ferred) fastened through the transverse axis
of C.

The triangular guards E are attached at *e e'*
to the rings B in such manner that the straight
line joining the central points of *e* passes
through one extremity, and the straight line
joining the central point of *e'* passes through
the other extremity, of the transverse axis of
plate C.

The damper being open, as in Fig. 1, by
turning the key D the rings B strike against
the interior of the stove-pipe A. By continu-
ing to turn, the loops are operated, and the
damper at the end of a quarter-turn gets into
the position shown in Fig. 2. By continuing
for another quarter-turn the damper gets into
the position Fig. 1 reversed, and to be fur-
ther operated must be returned. The damper
does not entirely cut off the draft; it simply
obstructs the passage of the products of com-
bustion.

Having thus described my invention, what
I claim as new, and desire to secure by Let-
ters Patent, is—

The triangular guards E, constructed as de-
scribed, attached at *e e'* to the rings B, as
herein set forth, for the purpose specified.

E. T. DUKE.
